UNITED STATES PATENT OFFICE

163,495

TOOTHPICK CASE

Nathaniel B. Valliant, Chicago, Ill.

Application August 28, 1950, Serial No. 11,958

Term of patent 3½ years

(Cl. D86—10)

To all whom it may concern:

Be it known that I, Nathaniel B. Valliant, a citizen of the United States, residing at Chicago, in the county of Cook and State of Illinois, have invented a new, original, and ornamental Design for a Toothpick Case, of which the following is a specification, reference being had to the accompanying drawing, forming part thereof.

I claim:

The ornamental design for a toothpick case, as shown.

NATHANIEL B. VALLIANT.
